[57] CLAIM

The ornamental design for a vehicle front, as shown and described.

DESCRIPTION

FIG. 1 is a left front perspective view of a vehicle front, showing our new design;

FIG. 2 is a front elevational view thereof;

FIG. 3 is a top plan view thereof;

FIG. 4 is a left side elevational view thereof; and,

FIG. 5 is a right side elevational view thereof.

The broken line showing of the hood is for illustrative purposes only, and forms no part of the claimed design.
